UNITED STATES PATENT OFFICE.

CLARENCE L. EATON, OF BOSTON, MASSACHUSETTS, ASSIGNOR TO THOMAS GUSTAVE PLANT, OF BOSTON, MASSACHUSETTS.

METHOD OF WAXING THREAD.

1,115,418.

Specification of Letters Patent. Patented Oct. 27, 1914.

Original application filed October 29, 1909, Serial No. 525,297. Divided and this application filed May 9, 1910. Serial No. 560,174.

To all whom it may concern:

Be it known that I, CLARENCE L. EATON, a citizen of the United States, residing at Boston, in the county of Suffolk and State of Massachusetts, have invented an Improvement in Methods of Waxing Thread, of which the following description, in connection with the accompanying drawings, is a specification, like letters on the drawings 10 representing like parts.

The invention to be hereinafter described relates to a method or process of waxing thread, and is a divisional of my prior application, Serial No. 525,297, filed October 15 29, 1909, now Patent No. 965,379, dated January 26, 1910, wherein an appropriate means is shown, described and claimed for carrying the present invention into effect.

The thread used for shoe sewing is ordinarily drawn from a source of supply and passed through a waxing device by which it is provided with a waxing composition. This waxing composition is formed of various ingredients, such, for instance, as paraffin and rosin, and in order that they be properly applied to the thread, such composition is ordinarily maintained in the liquid state by the application of heat. On the one hand it is desirable that the waxing composition be kept heated to a high temperature and in the liquid state, while on the other hand it should not be permitted to become overheated; because, when so overheated, the ingredients composing the 35 waxing composition become so far separated that the composition is spoiled so far as its use for thread waxing is concerned, as is well understood by those skilled in the art; and, moreover, the composition boils and 40 runs over the top of its container when so overheated.

The aims and purposes of the present invention are to provide a process or method of waxing thread, whereby the waxing composition may be maintained at a desirable high temperature and in the liquid state, and yet be effectually prevented from becoming injuriously overheated, all of which will hereinafter appear in connection with 50 the accompanying drawings which show a means for carrying out the process or method.

In the drawings:—Figure 1 is a side view of any usual or desired form of waxing

tank which may be secured to the wax 55 thread sewing machine and used in connection therewith, if desired; and Fig. 2 is an end view thereof with parts broken away to show the elements beyond, said figures illustrating one form of means for carrying 60 the present method or process into practical effect.

The waxing tank 1 may be of any usual or desired character, and preferably may be formed of cast metal provided with a 65 suitable supporting bracket 2 by which it may be secured to the frame of a wax thread sewing machine, or elsewhere, as indicated in Fig. 1.

Disposed at the bottom portion of the 70 waxing tank 1 there is a heating chamber 3 connected at one part by means of a pipe 4 with a source of steam or hot air supply, and at another portion provided with a discharge pipe 5, as indicated in Fig. 1. In 75 these respects, as well also as with respect to the inlets 6 and 7 for the thread 8 to be waxed, the waxing tank may be of any usual or desired character, and the waxing composition may be maintained in a heated 80 condition by any suitable or desired means, it being understood that with respect to these features the invention is generally applicable.

As well understood by those skilled in the 85 art, the waxing composition when supplied to the trade is in solid form and among its constituent elements there is paraffin and rosin. For the proper application of this composition to the thread, it is first heated 90 in order to reduce it to a liquid state and maintain it at a sufficiently high temperature to make such composition thoroughly liquid, so that it will properly wax the thread as the latter is drawn through it. 95

In practice it has been found that the waxing composition frequently reaches a temperature sufficiently high to cause the constituents thereof to separate and thus impair the quality of the composition and 100 of the thread treated thereby. Under the objectionable conditions noted the thread will become treated by less than the full complement of the ingredients composing the composition, and if, as usually happens, the thread should be principally treated by the resinous substance of the wax, it will become brittle and readily break during the 105

sewing operation or after the treated thread has become cold. Moreover, under the conditions above noted, the waxing composition is liable to boil over the waxing tank and 5 run upon the floor, thus engendering great waste of material. These objectionable characteristics are overcome by the present invention, which contemplates a process or method of treating the waxing composition, 10 whereby it may be maintained in the desired liquid condition and at the desired temperature without at the same time endangering separation of the ingredients of the composition by overheating, the thread being 15 drawn through such composition and treated thereby, as will presently appear.

As one form of means for practising the method or process, the drawings show a waxing tank 1 provided with suitable bearings 9 and 10 in which is supported a shaft 11 having secured thereto a series of buckets 12 which dip into the waxing composition in the tank 1 and, by rotation of said shaft, stir the composition in the tank and lift 25 portions thereof from the tank and then, as the shaft revolves, said buckets permit the portions of the waxing composition raised by them and cooled somewhat to run back into the waxing tank.

30 As one means of operating the shaft 11, said shaft is projected through one side of the tank, as indicated in Fig. 1, and provided with a worm wheel 13 which is engaged by a worm 14 on a suitable shaft 15, said shaft 15 being preferably provided with a clutch member 16 adapted to engage a complementary clutch member 17 connected to a pulley 18, or other means, which may be driven from a suitable source of power. 35 The clutch members may be caused to engage by suitable hand operating devices, as the wheel 19 secured to the hub of the driving pulley 18.

Obviously changes may be made in the 45 general form and character, both of the tank, heating means for the waxing composition, and the driving or operating devices for the cooling buckets; and it will be clearly apparent that the cooling buckets 50 may be operated in any manner desired, the characteristics of the invention in this respect being that they be constructed so that when in operation they will dip down into

the waxing composition and lift portions thereof from the tank, thereby enabling such 55 portions to become cooled to some extent, and then permit such portions to run back into the waxing tank. By this characteristic operation it will be noted that not only is the waxing composition kept thoroughly 60 mixed, but it is prevented from attaining a temperature calculated to injure the waxing composition or cause it to overflow from the tank.

What is claimed is:

1. The process or method of waxing sewing thread which consists in subjecting the waxing composition to heat to maintain the same in liquid state, removing portions of the liquid composition from the mass from 70 time to time during the application of heat thereto and returning such portions after they have been sufficiently cooled to prevent separation of the ingredients of the composition in the body of the liquid by overheating, and simultaneously commingling and stirring the main body of the mixture and passing a thread through the said main body of the composition at a point where the desired temperature and mixture of the composition is maintained.

2. The process or method of waxing sewing thread as it is delivered to the sewing devices which consists in subjecting the waxing composition to the continued action of 85 heat to maintain the said composition in easily flowing liquid form, cooling portions of said liquid waxing composition at intervals during the application of heat to the body of the said composition and causing 90 the said cooled portions to intermingle with the lower body portions of the composition to prevent overheating of such lower body portions and consequent separation of the ingredients at such point, and simultaneously drawing a thread through the said lower body portion of the composition where the desired temperature and character of 95 composition is maintained.

In testimony whereof, I have signed my 100 name to this specification, in the presence of two subscribing witnesses.

CLARENCE L. EATON.

F. H. Rowsom.

Correction in Letters Patent No. 1,115,418.

It is hereby certified that Letters Patent No. 1,115,418, granted October 27, 1914, upon the application of Clarence L. Eaton, of Boston, Massachusetts, for an improvement in "Methods of Waxing Thread," were erroneously issued to Thomas Gustave Plant, as assignee of the entire interest in said invention, whereas said Letters Patent should have been issued to *United Shoe Machinery Company, of Paterson, New Jersey, a corporation of New Jersey*, as assignee by mesne assignments of the entire interest in said invention, as shown by the records of assignments in this office; and that the said Letters Patent should be read with this correction therein that the same may conform to the record of the case in the Patent Office.

Signed and sealed this 24th day of November, A. D., 1914.

[SEAL.]

R. F. WHITEHEAD,
Acting Commissioner of Patents.
